UNITED STATES PATENT OFFICE

2,285,460

SCREW

William A. Purtell, West Hartford, Conn., assignor to The Holo-Krome Screw Corporation, a corporation of Connecticut

Application May 26, 1939, Serial No. 275,902

15 Claims. (Cl. 85—45)

My invention relates to screws.

More particularly, it relates to screws of a type adapted to be produced by a modified form of the method and apparatus described and claimed in my copending application Serial No. 275,904, filed May 26, 1939; a further type of such screw also being described and claimed in my copending application Serial No. 275,903, filed May 26, 1939.

It has among its objects to provide an improved socketed screw suitable for use in wood, metal, or other materials. A further object of my invention is to provide such a screw having improved socket means of an improved conformation and adapted to cooperate in an improved manner with a screw driver and to provide an improved target for the latter. Still another object includes the provision of such an improved screw wherein the socket forming aperture is of such improved structure as to facilitate the insertion of the screw driver and retain the screw thereon in such manner as markedly to speed up the process of screw insertion, while also increasing the strength of the head and minimizing marring thereof during use. These and other objects and advantages of my improved construction will, however, hereinafter more fully appear.

In the accompanying drawing, I have shown for purposes of illustration certain embodiments which my invention may assume in practice.

In the drawing:

Figure 1 is a top plan view of my improved screw;

Fig. 2 is a section on line 2—2 of Figure 1, the threaded lower end of the screw being broken away to facilitate illustration;

Fig. 3 is a sectional view of the head similar to that in Figure 2, the view being taken on line 3—3 of Figure 1;

Fig. 4 is a section on line 4—4 of Figure 2;

Fig. 5 is a section on line 5—5 of Figure 2;

Fig. 6 is a view similar to Figure 2 but showing a screw driver in process of insertion in the socket in the head of the screw;

Fig. 7 is a view similar to Figure 2, but with the screw driver inserted in the socket;

Fig. 8 is a view similar to Figure 3, but with the screw driver inserted in the socket;

Fig. 9 is a side elevation of the driver, and

Fig. 10 is a view similar to Figure 7 showing a modified form of screw driver in position in the socket.

In this illustrative construction, the screw, generally indicated at 1, has a shank 2 provided at one end with suitable threads 3 thereon and

5 at the other end with a head 4; this head 4 herein being provided with an improved socket, generally indicated at 5, in the top thereof, which is adapted to cooperate in an improved manner with a screw driver 7, all as hereinafter more fully described.

Referring to the socket 5, it will be noted that while not limited to the number of flutes illustrated, I have shown herein six grooved or fluted portions 8 opening radially into the socket 5, such a number being found to be desirable in increasing the facility with which the socket 5 may be formed, and also that with which a screw driver may be inserted in this socket. Further, it will be observed that each of these portions 8 is provided with a convexly curved, radially located, ribbon-like, end or outer wall 9 extending downward from the top of the head 4 to the bottom of the socket 5, as shown in Figure 2. As clearly appears from Figures 4 and 5, these walls 9 decrease slightly in width from the top to the bottom of the socket. Moreover, each of the portions 8 is provided with laterally concave side walls 10 diverging from the opposite edges of the walls 9. Side walls 10 of adjacent fluted portions also intersect at the inner edges of these walls 10, thereby forming a vertically curved edge 11, more steep in its inclination than the walls 9 and constituting the apex of an intermediate 20 abutment 12 provided between adjacent fluted portions 8.

Thus, the socket 5 is provided with a large target or mouth, the whole area within a circle 30 passing through the upper ends of the edges 11, being open. Further, the convex surfaces 9 are so disposed in this large mouth as to produce tool guiding surfaces leading gradually toward the axis and bottom of the socket, in such manner that a screw driver extremity engaging at 40 any point on these surfaces 9 tends to be automatically centered. Attention is also directed to the fact that the angle of the inner ends of the convex surfaces 9, herein indicated at 9a, relative to the axis of the socket is so small as to enable 45 a very definite binding or wedging effect to be obtained at the inner end 9a of each surface 9, this effect obviously decreasing as the socket flares outward toward the mouth of the socket where, in order to facilitate insertion of the screw driver, binding is not desired.

Receivable in my improved socket 5 is a screw driver 7, which is adapted to cooperate therewith to enable improved results to be obtained. Herein, the driver 7 is provided with radial wing portions, generally indicated at 13, and correspond-

ing in conformation to the fluted portions 8 in which they are adapted to be received and fit, as shown in Figures 7 and 8. More particularly, each of these portions 13 tapers toward the extremity of the driver and has a concave, outer, ribbon-like, edge portion 14, corresponding to the wall 9 and adapted to engage the latter as shown in Figure 7, while each portion 13 also is provided with laterally convex side walls 15, corresponding to and engageable with the walls 10 and adapted to engage these walls 10 when the edge portions 14 are engaging the walls 9. Further, these walls 15 intersect on a concave line 16 as shown in Figure 8, in such manner as thereby to receive the convex intersection 11 of the adjacent walls 10.

As a result of the cooperation of my improved socket 5 and the driver 7, when the latter has its working end inserted in the socket, the inner more abruptly angled portions 9a of the convex surfaces 9 will engage corresponding portions on the inner ends of the surfaces 14 on the wing portions 13 in such manner as to produce sufficient binding at the inner end of the socket to insure the connection of the screw and driver. Further, it will be apparent that when the screw driver is thus inserted, as shown in Figures 7 and 8, the entire working end of the screw driver, including the surfaces 14 and 15, will be in contact with the corresponding surfaces 9 and 10 on the socket throughout the length of the portion of the screw driver which is received in the socket. Here it will also be noted that, as preferably and as shown in these figures, the length of the working end of the screw driver is such as to space its inner end slightly from the bottom of the socket.

In the use of my improved construction, the enlarged mouth provided in the socket 5 by the several large upper ends of the fluted portions 8, is such as markedly to facilitate the insertion of the screw driver 7, the size of the opening or so-called "target" thus provided for the screw driver in the head of the screw, being such as markedly to facilitate and speed up the insertion of the screws. Further, the convex surfaces 9 act to guide the smaller or entering ends of the wing portions 13 of the screw driver 7 toward the axis of the screw, in such manner as thereby further to facilitate connection and disconnection of the driver and screw. It will also be particularly noted that as the screw driver moves inward with its concave surfaces 14 riding along the convex surfaces 9, the binding effect gradually increases until the inner ends of the walls 14 on the wing portions 13 are quite snugly engaged with the inner portions 9a of the corresponding convex walls 9, the grip obtainable being such as to permit the driver to be handled substantially at will without loss of the screw therefrom. Further, it will be apparent that all of the working surface of the socket 5 will also be engaged by corresponding surfaces on the working end of the screw driver 7 and that this engagement will be maintained by the binding effects obtained by the portions of the surfaces 9, 10 and 11 corresponding to and including the portions 9a and disposed in a shallow zone around the axis of the screw at the bottom of the socket. Attention is also particularly directed to the fact that upon turning of the driver about its axis, the several side walls 15 on the wing portions 13 thereof will produce an effective turning movement of the screw with a minimum of destructive camming action on the walls of the socket, tending to explode the latter;

the engagement of the walls 15 with the corresponding surfaces 10 on the latter thus acting to minimize any tendency to mutilate the abutments 12 or tear the walls of the screw.

5 In Figure 10, I have illustrated a modified driver construction which may be used, if desired. In this construction, instead of a surface 14 on the wing portion 13 of the screw driver, a surface 17 is provided, which, while corresponding to the surface 14 in having a cooperating binding or wedging portion at its inner end, slopes further away from the corresponding surface 9 on the screw toward the mouth of the socket. In this construction, obviously the inner end portions 9a of the various surfaces 9 will cooperate with the inner ends of the various surfaces 17 to produce the desired binding effect, even if the remainder of the surfaces 17 does not fit the remainder of the surface 9, all while continuing to obtain other advantages of my improved construction, heretofore described.

As a result of my improved construction, it is made possible for the screws to be inserted in the work with increased speed and facility, due to the 25 larger target provided by my improved socket 5 and to the guiding action exerted by the convex surfaces on the screw driver. Further, the screw is securely maintained upon the driver by the wedging action in the shallow zone adjacent the 30 bottom of the socket, upon the mere bringing together of the screw and driver and without any conscious connecting effort on the part of the user, while the binding or wedging action is such as, of course, to permit the ready withdrawal of 35 the screw driver or removal of the screw, whenever desired. Attention is also particularly directed to the more even distribution of the metal in the socket walls present in my improved construction which is such as to eliminate the 40 need for severe displacements of the metal during the socket forming operation, and also to produce a stronger head. Further, the construction is such as to enable the screws to be made quickly and satisfactorily in an ordinary header and eliminate necessity for shearing the top and 45 the undersurface of the head, all in such manner as markedly to reduce the manufacturing cost of the same. These and other advantages of my improvements will, however, be clearly apparent to those skilled in the art.

50 No claim is made herein to the turning tool or driver, or the combination thereof with the socketed screw, this subject matter being claimed in a divisional application Serial No. 433,031, filed March 2, 1942.

55 While I have in this application specifically described certain forms which my invention may assume in practice, it will be understood that these forms of the same are shown for purposes of illustration, and that the same may be modified and my invention embodied in various other forms without departing from its spirit or the scope of the appended claims.

What I claim as new and desire to secure by Letters Patent is:

65 1. A socketed connector having a turning socket therein, and turning tool binding means, including a binding portion adjacent the bottom of said socket and disposed at increasingly acute binding angles toward said bottom, for engaging a generally correspondingly angled reciprocably inserted tool at a binding angle adjacent the bottom of said socket.

70 2. A socketed connector having a turning socket therein, and turning tool binding means

75

including a plurality of binding portions adjacent the bottom of said socket and disposed at increasingly acute binding angles toward said bottom, for engaging a generally correspondingly angled reciprocably inserted tool at wedging angles adjacent the socket bottom and at a plurality of locations surrounding the socket axis while the inner extremity of said tool is spaced above the socket bottom.

3. A socketed connector having a turning socket therein, and turning tool binding means in said socket having a binding portion leading toward the bottom thereof and also having increasingly acute binding angles on said portion.

4. A socketed connector having a turning socket therein including radially located fluted portions, and turning tool binding means having binding portions on the bottom ends of certain of said fluted portions and disposed at increasingly acute binding angles toward the bottom of said socket.

5. A socketed screw having a turning socket therein including radially located fluted portions, and having elongated convex turning tool binding means around the inner end of said socket and disposed at increasingly acute binding angles toward the bottom of said socket.

6. A socketed screw having a turning socket therein including radially located fluted portions, and also having elongated convex turning tool binding end wall portions in certain of said fluted portions disposed at increasingly acute angles to the screw axis toward the bottom of said socket.

7. A socketed screw having a turning socket therein including radially located fluted portions, and also having convex end wall portions in said fluted portions, and side walls on said fluted portions having elongated binding portions adjacent the bottom of the socket disposed at increasingly sharp angles to the screw axis toward the bottom of said socket.

8. A socketed screw having a turning socket therein including radially located fluted portions and turning tool abutments therebetween, and also having convex end wall portions in said fluted portions, and binding portions on the edges of said abutments adjacent the socket axis having elongated binding portions adjacent the bottom of the socket disposed at increasingly sharp angles to the screw axis toward the bottom of said socket.

9. A socketed screw having a turning socket therein including radially located fluted portions and turning tool abutments therebetween, and also having a plurality of binding walls in said socket leading toward the bottom thereof, the inner portions of said walls being convex and approaching the axis of the screw at increasingly sharp binding angles.

10. A socketed screw having a turning socket therein including radially located fluted portions, and also having end walls in said fluted portions, the inner portions of said walls being convex and

approaching the axis of the screw at increasingly sharp binding angles, and the remainder of said socket having like sharply angled binding surfaces therein disposed in a shallow transverse peripheral zone adjacent the bottom of the socket.

11. A socketed screw having a turning socket therein including radially located fluted portions, and having binding portions wholly in the inner end of said socket and comprising vertically convex binding surfaces on the inner ends of said binding portions and approaching the axis of the screw at increasingly sharp binding angles toward the bottom of the socket.

15. 12. A socketed screw having a turning socket therein including radially located fluted portions opening into said socket, and turning abutments between said fluted portions, said fluted portions having convex end walls and said walls having binding portions on their inner ends approaching the axis of the screw at increasingly sharp binding angles toward the bottom of the socket and said abutment portions having longitudinally disposed convex binding portions between their opposite sides.

20. 13. A socketed screw having a turning socket therein including radially located fluted portions opening into said socket, and turning abutments between said fluted portions, said fluted portions having convex end walls and said walls having binding portions on their inner ends approaching the axis of the screw at increasingly sharp binding angles toward the bottom of the socket and also having side walls forming the side walls of said abutments and cooperating to form binding portions and intersecting along longitudinally disposed convex lines.

30. 14. A socketed connector having a turning socket therein including radially located fluted portions disposed in intersecting longitudinal planes, around the axis of said socket and having short side walls on said portions cooperating to provide an enlarged axial target, and turning tool binding means disposed in the bottom of said socket having radially located binding portions disposed at increasingly sharp binding angles toward the bottom of said socket.

35. 15. A socketed connector having a turning socket therein including oppositely extended fluted portions disposed in the same longitudinal plane and a plurality of like oppositely located and equally spaced fluted portions disposed on opposite sides of said plane, said fluted portions being disposed around the axis of said socket and adjacent fluted portions having short intersecting side walls cooperating to provide an enlarged target, and turning tool binding surfaces disposed around the bottom of said socket having elongated vertically convex binding surfaces in the bottom of said socket disposed at increasingly sharp binding angles toward said socket bottom.

WILLIAM A. PURTELL.
